UNITED STATES PATENT OFFICE.

PHILIP T. DODGE, OF NEW YORK, N. Y., ASSIGNOR TO MERGENTHALER LINOTYPE COMPANY, A CORPORATION OF NEW YORK.

TYPOGRAPHICAL MACHINE.

1,079,478.

Specification of Letters Patent.

Patented Nov. 25, 1913.

Application filed December 18, 1912. Serial No. 737,387.

To all whom it may concern:

Be it known that I, PHILIP T. DODGE, a citizen of the United States, residing at New York, in the county of New York and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States to O. Mergenthaler, No. 436,532, wherein matrices are 15 stored end to end in a channeled magazine, and are released therefrom by suitably actuated escapement devices. When so released, they are conveyed to a common point and there assembled side by side in line. The 20 composed line is then transferred to the face of a slotted mold, the mold filled with molten metal to form a slug or linotype against the matrices which produce the type characters thereon, and the matrices there- 25 after returned by a distributing mechanism to the mazagine from which they started.

In practice, it has been found that the 30 matrices fall onto each other in the magazine with considerable force (particularly the large or thick matrices), and as a result thereof soon become battered and worn. In addition, the delicate escapement devices which support the matrices in the magazine, also become worn or broken or otherwise 35 damaged, as a consequence of the repeated shocks. These objections are accentuated in the longer magazines; and in vertically disposed magazines, wherein practically the full force of gravity is allowed to exert it- 40 self; and also when the channels of the magazine are empty or nearly so, as then the matrices necessarily acquire greater momentum.

It is the object of my invention to over- 45 come these objections, and to that end I have provided means to engage and retard the matrices in their fall. As a suitable means for accomplishing this purpose, I have illustrated a roll extending across the 50 magazine and projecting into the channels thereof, so as to engage the matrices as they drop into place.

In the accompanying drawing, I have shown my invention merely by way of ex- 55 ample and in preferred form, and as ap-

plied to the specific kind of machine already mentioned, but obviously many changes and variations may be made therein, and similarly it may be used in connection with other forms of typographical machines, such as handle type, dies, etc., without departure from its spirit; and generally speaking, I desire it to be understood that I do not limit myself to any specific form or embodiment, except in so far as such 65 limitations are specified in the claims.

Referring to the drawing: Figure 1 is a vertical section through the inclined magazine, the distributing mechanism, etc., of a linotype machine, having my invention applied thereto. Fig. 2 is a similar view showing a vertically disposed magazine, and my invention in modified form; and Fig. 3 is a transverse section on the line 3—3 of Fig. 1. 75

The matrices X are stored in the channeled magazine A, which may be supported in the inclined position shown in Fig. 1, or in the vertical position shown in Fig. 2. The matrices are released from the magazine 80 by the escapement devices B, operated through the reeds C, from the customary key-board mechanism, and then pass through the face-plate D to the other assembling devices, and thence to the casting mechanism. 85 After the casting operation, the matrices are delivered to the distributing mechanism, comprising the grooved rail or bar E and the rotating screws F, which carry the matrices along the bar until they drop there- 90 from into their respective channels in the magazine A. As thus far described, the parts and operations are or may be substantially the same as those set forth in the before-mentioned Mergenthaler patent, or as 95 embodied in the commercial linotype machine.

Turning now to my improvement, in order to check or retard the falling matrices, I provide means, preferably in the form of a 100 rotating roll, having a velocity less than that of the falling matrices, and extending transversely across the magazine, and projecting through an aperture therein, so as to engage with the matrices, as they pass into place in their channels. Referring to Figs. 1 and 3, the roll H is mounted to turn in bearings H1 on the magazine supporting frame A1, and is rotated by the pulley I and the band or cord J, from some convenient part 105 110

of the machine, such as the shaft K. The roll H may be placed in any suitable position to engage the matrices during their fall, but I prefer to locate it mid-way between the ends of the magazines, and also so that when the matrices are at rest, it will turn in the space between the upper and lower ears of the contiguous ones, as shown in Fig. 2, and in such manner that normally the roll will have no effect in urging the matrices downward. It will be apparent that by varying the speed of rotation of the roll H, the matrices may be caused to drop into place with substantially any force desired.

In place of the power-driven roll H shown in Fig. 1, I have illustrated in Fig. 2, an idle roll L mounted in any suitable manner and similarly located with respect to the matrices in the magazine. This roll L also acts to check the falling matrices, although perhaps not with such precision and capability of control as the roll H. It will of course be obvious that if desired, two such rolls H or L may be employed, one on each side of the magazine, and at opposite points thereof, or that any number may be located at various points on both sides of the magazine, as will be suggested by convenience or the amount of retardation sought to be secured.

As previously stated, my invention may be carried into effect by other forms of devices, which may vary widely from those shown in the present instance, both in construction and operation, and still be comprised within its scope. Such variations and modifications will readily suggest themselves to those skilled in the art.

Having thus described my invention, its construction and mode of operation, what I claim and desire to secure by Letters Patent of the United States, is as follows:

1. In a typographical machine, the combination of a magazine for the type or matrices, and a device located between the ends of the magazine in position to engage the edges of the type or matrices and thus retard them as they pass into place therein. 40

2. In a typographical machine, the combination of a magazine for the type or matrices and a rotatable roll projecting into the magazine so as to engage and retard the type or matrices as they pass into place therein. 50

3. In a typographical machine, the combination of a magazine for the type or matrices and a constantly rotating roll projecting into the magazine so as to engage and retard the type or matrices as they pass to place therein, the said roll having a velocity less than that of the passing type or matrices. 60

4. In a typographical machine, a magazine to contain type or matrices having projecting ears, and provided with a rotatable roll to engage and retard the type or matrices in their passage into place therein, the said roll being located in the space between their projecting ears when the type or matrices are at rest. 65

In testimony whereof I affix my signature in presence of two witnesses.

PHILIP T. DODGE.
